UNITED STATES PATENT OFFICE.

GEORGE W. BAUGHMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRICAL RELAY.

Application filed October 4, 1924. Serial No. 741,752.

My invention relates to electrical relays, and particularly to relays of the alternating current type responsive selectively to current of one frequency but not to current of another frequency.

I will describe one form of relay embodying my invention, and will then point out the novel features thereof in claims.

In the accompanying drawing, Fig. 1 is a plan view showing one form of relay embodying my invention and is also a diagrammatic view showing one form of apparatus with which the relay may be used. Fig. 2 is a view showing in side elevation the relay illustrated in Fig. 1. Fig. 3 is a sectional view on the line III—III of Fig. 1. Fig. 4 is a sectional view on the line IV—IV of Fig. 2. Fig. 5 is a sectional view on the line V—V of Fig. 1.

Similar reference characters refer to similar parts in each of the several views.

Referring to the drawing, the relay, which is designated as a whole by the reference character R, comprises a magnetizable core 2 preferably of laminated soft iron, which core is provided with two paths for magnetic flux. One of these paths includes a pair of pole pieces 3 and 3^a separated by an air gap 4, whereas the other path comprises a pair of pole pieces 5 and 5^a separated by an air gap 6.

The relay is provided with two windings 8 and 9. The winding 8 is located on a cross piece 28 forming part of the main body 35 of the core 2 of the relay, so that the magnetic flux created by this winding tends to flow through the two paths of pole pieces. The other winding 9 is of the strap type, that is, it comprises a single strap of electro-conductive material, and this winding is mounted on the pole pieces 3, 3^a, 5 and 5^a, as illustrated in Figs. 3, 4 and 5. To accommodate this winding each pole piece is slotted, as indicated at 25 and 25^a in Fig. 5. The winding 9 is in the form of a letter S 45 on pole pieces 3 and 5, as illustrated in Fig. 3, whereas on each pole piece 3^a and 5^a this winding merely passes through the slot 25^a. Referring particularly to Fig. 5, it will 50 be observed that the winding 9 when supplied with alternating current creates a magnetic flux which flows in pole pieces 5 and 5^a in the path indicated by the arrows. This winding creates flux which flows in the same

manner in pole pieces 3 and 3^a. If the alternating currents supplied to the two windings 8 and 9 are of the same frequency but are displaced in phase, a shifting magnetic field will be created in each air gap 4 and 6, the direction of shift on the air gaps being the same; that is, if the magnetic field in either air gap shifts upwardly, the magnetic field in the other air gap will also shift upwardly, and vice versa.

As shown in the drawing, the area of each pole piece 3 and 3^a is smaller than the area of each pole piece 5 and 5^a. It follows that unless other means were provided the magnetic field in air gap 6 would be stronger than the magnetic field in air gap 4. Pole pieces 5 and 5^a, however, are provided with closed conductors 7 and 7^a, respectively, as illustrated in Figs. 1 and 5, the effect of which is to increase the reluctance offered to fluxes passing through air gap 6.

The relay is provided with a movable member which is acted upon by the shifting magnetic fields in the air gaps 4 and 6. In the form here shown, this member is a vane 10 of non-magnetizable electro-conductive material, such as aluminum, which vane is mounted on a shaft 11. The vane 10 is so disposed as to be oppositely affected by the shifting fields in the two air gaps, and inasmuch as these fields both shift in the same direction, the vane is mounted with its pivotal point between two pairs of pole pieces. It follows that the shifting field in air gap 4 will tend to move the vane in one direction, such for example, as in counter-clockwise direction, whereas the shifting field in the air gap 6 will tend to move the vane in the other direction, such, for example, as in clockwise direction. The vane 10 is biased to one position by any suitable means, such, for example, as a counterweight 14, and this vane controls a contact 13 in such manner that when the vane occupies the position to which it is biased by the counterweight this contact is open, whereas, when the vane is shifted in counter-clockwise direction from such biased position, the contact is closed. As here shown, contact 13 is operatively connected with an arm 12 fixed to the shaft 11 on which the vane is mounted.

The parts of the relay are so designed and adjusted that when the windings 8 and 9 are supplied with alternating current of a given

frequency the shifting magnetic fields in the air gaps 4 and 6 exert equal torque on the vane 10, so that contact 13 remains open. When the current supplied to the relay windings are of a different frequency, however, such, for example, as a higher frequency, the closed conductors 7 and 7^a reduce the amount of flux in the pole pieces 5 and 5^a and increase the amount of flux in pole pieces 3 and 3^a, so that the torque exerted on the vane 10 by the shifting magnetic field in air gap 4 is greater than the torque exerted on this vane by the shifting magnetic field in air gap 6. The vane 10 then moves in counter-clockwise direction, as viewed in Fig. 2, so that it closes contact 13.

Relays embodying my invention are particularly well adapted for use in railway signaling systems, such, for example, as the system illustrated diagrammatically in Fig. 1. Referring to this view, the reference characters 15 and 15^a designate the track rails of a railway, which rails are divided by insulated joints 16 to form an insulated track section A—B. These rails are supplied with alternating propulsion current from a generator G^p, the terminals of which are connected with the rails through balanced bonds 27. The rails are provided, as usual, with bonds 26 to conduct the propulsion current around the insulated joints 16. Track section A—B is provided with a track circuit which is constantly supplied with alternating signaling current from a generator G^s, through the medium of line wires 19 and 19^a, which wires are connected across the rails of the section by wires 20 and 20^a. Winding 8 of relay R is also connected across the rails of section A—B by wires 17 and 18, and winding 9 is constantly supplied with alternating current from the generator G^s through a transformer T, the secondary of which is connected with the winding 9, and the primary of which is connected with wires 19 and 19^a through the medium of wires 21 and 21^a. Section A—B is provided with a signal S which is controlled by a circuit passing from wire 19, through wire 22, operating mechanism of signal S, wire 23, contact 13 of relay R, and wire 24 to line wire 19^a.

The propulsion current supplied by generator G^p and the signaling current supplied by generator G^s differ in frequency; for example, the propulsion frequency may be 25 cycles per second, and the signaling frequency may be 60 cycles per second. The relay R is so designed and proportioned that when 60 cycle current is supplied to both of the windings 8 and 9 a torque is created on the vane 10 tending to shift this vane in counter-clockwise direction as viewed in Fig. 2, thereby closing contact 13 and causing signal S to indicate proceed. If, however, current of the propulsion frequency

should be supplied to both windings 8 and 9 due to any defect in the apparatus, the effect of this current would be to equalize the torques exerted on vane 10 by the shifting magnetic fields in air gaps 4 and 6, so that this vane would move to or remain in its biased position wherein contact 13 is open, so that signal S would indicate stop.

As shown in Fig. 1, section A—B is occupied by a train C, the wheels and axles of which shunt the signaling current away from winding 8. Winding 8 being de-energized, there are no shifting magnetic fields in the air gaps 4 and 6, so the vane 10 is in the biased position wherein contact 13 is open and signal S indicates stop. When the train C passes out of section A—B, signaling current will be supplied to winding 8, and so the relay will be actuated to close contact 13, whereupon signal S will move to the proceed position.

Although I have herein shown and described only one form of relay embodying my invention, it is understood that various changes and modifications may be made therein within the scope of the appended claims without departing from the spirit and scope of my invention.

Having thus described my invention, what I claim is:

1. A relay comprising a first operating winding, a core for said winding having two paths for the flux created by the winding, each path including a pair of pole pieces separated by an air gap, a second operating winding located wholly on said two pairs of pole pieces, and arranged to receive alternating current from a source outside of the relay, and a movable member mounted to be oppositely affected by the fluxes traversing said two air gaps. 95

2. A relay comprising a first winding, a core for said winding having two paths for the flux created by the winding, one path including a first pair of pole pieces of relatively small area separated by an air gap and the other path including a second pair of pole pieces of relatively large area separated by an air gap, a second winding associated with said two pairs of pole pieces, closed conductors associated with the pole pieces of said second pair whereby the distribution of flux in said two air gaps due to current in each winding varies with variations in the frequency of the current supplied to the winding, and a movable member mounted to be oppositely affected by the fluxes traversing said two air gaps. 110

3. A relay comprising a first winding, a core for said winding having two paths for the flux created by the winding, each path including a pair of pole pieces separated by an air gap, a second winding associated with said two pairs of pole pieces, closed conductors associated with the pole pieces of 115

one pair but not with the other whereby the distribution of flux in said two air gaps due to current in each winding varies with variations in the frequency of the current supplied to the winding, and a movable member mounted to be oppositely affected by the fluxes traversing said two air gaps.

4. A relay comprising a core having two paths for the flow of magnetic flux, each 10 path including a pair of pole pieces separated by an air gap, two windings associated with said core whereby when said windings are supplied with currents differing in phase a shifting magnetic field is 15 created in each air gap, closed conductors associated with the pole pieces of one pair but not with the other whereby the distribution of flux in said two air gaps due to current in each winding varies with variations 20 in the frequency of the current supplied to the winding, and a movable member mounted to be oppositely affected by the shifting magnetic fields in said two air gaps.

5. A relay comprising a core having two paths for the flow of magnetic flux, one path 25 including a first pair of pole pieces of relatively small area separated by an air gap and the other path including a second pair of pole pieces of relatively large area separated by an air gap, two windings as 30 sociated with said core whereby when said windings are supplied with alternating currents differing in phase a shifting magnetic field is created in each air gap, closed conductors associated with the second pair of 35 pole pieces but not with the first whereby the distribution of flux in said two air gaps due to current in each winding varies with variations in the frequency of the current supplied to the winding, and a movable 40 member to be oppositely affected by the shifting magnetic fields in said two air gaps.

In testimony whereof I affix my signature.

GEORGE W. BAUGHMAN.
